UNITED STATES PATENT OFFICE

156,395

TELEVISION CABINET

Arthur P. Young, Newark, and William Maslo,
Jersey City, N. J.

Application June 26, 1948, Serial No. 147,234

Term of patent 3½ years

(Cl. D56—4)

To all whom it may concern:

Be it known that we, Arthur P. Young, a citizen of the United States, residing in Newark, county of Essex and State of New Jersey, and William Maslo, a citizen of the United States, residing in Jersey City, county of Hudson, and State of New Jersey, have invented a new, original, and ornamental Design for a Television Cabinet, of which the following is a specification, reference being had to the accompanying drawing, forming part thereof.

In the drawing:

Fig. 1 is a plan view of a television cabinet, showing my new design;

Fig. 2 is a front elevational view thereof; and
Fig. 3 is a side view thereof.

We claim:

The ornamental design for a television cabinet, as shown.

ARTHUR P. YOUNG.
WILLIAM MASLO.
